UNITED STATES PATENT OFFICE.

JOSEPH H. HINES, OF PHILADELPHIA, PENNSYLVANIA.

SPARK-ARRESTER.

No. 874,768.

Specification of Letters Patent.

Patented Dec. 24, 1907.

Application filed August 19, 1907. Serial No. 389,212.

To all whom it may concern:

Be it known that I, JOSEPH H. HINES, a citizen of the United States, residing at Philadelphia, in the county of Philadelphia and State of Pennsylvania, have invented certain new and useful Improvements in Spark-Arresters; and I do declare the following to be a full, clear, and exact description of the invention, such as will enable others skilled in the art to which it appertains to make and use the same.

This invention relates to spark arresters, and more particularly to such a device for use upon locomotives, and it has for its object to provide a device whereby sparks will be prevented from issuing from the smoke stack of the locomotive without interfering with the draft from the fire-box.

Broadly speaking, the device comprises a revolving screen placed at the lower end of the smoke stack, and a rotary cleaner adapted to engage therewith and thereby simultaneously rotate the arrester and remove particles that may have been caught and would otherwise obstruct the draft.

In the accompanying drawings, Figure 1 is a broken perspective view of the forward end of a locomotive provided with my improvement; and Fig. 2 is an end elevation of the same.

Referring more particularly to the drawings, 1 indicates the boiler of a locomotive having the usual smoke box, 2, at its forward end. Journalized in the smoke box, preferably by means of hangers, 3, and a shaft, 4, is a rotary screen, 5.

A rotary cleaner, 6, is mounted adjacent to the screen 5 preferably by being journalized in one of the arms, 7, of the hangers, 3, in position for engaging with the surface of the screen, 5, and thereby rotating the same. The cleaner is provided with teeth or projections, 8, which are adapted to enter the perforations, 9, in the screen and thereby dislodge any sparks, soot, or other matter that may have collected therein and would have a tendency to obstruct or interfere with the draft or discharge of the products of combustion from the smoke box into the smoke stack. The cleaner can be actuated in any desired manner, as by a flexible shaft, 10, which is connected with the shaft 12 of the cleaner in any desired manner and is driven from any suitable portion of the

driving mechanism of a locomotive (not shown).

The cleaner is made of a less diameter than the smoke box and is preferably placed at a distance from the top, so as to permit of the free circulation of the smoke around it in order for it to pass as freely as possible through the perforations therein. This necessitates the extension of the lower end of the smoke stack, 13, down into the smoke box, with its lower end preferably expanded, as shown at 14, and scalloped or recessed semi-circularly, as shown at 15, so as to correspond with the curvature of the screen. In this manner, it is impossible for any spark to pass from the smoke box without engaging with the screen, and thereby being prevented from passing out of the smoke stack and setting fire to buildings or grain along the track.

The rotation of the cleaner will prevent the clogging of the screen, whereby the draft will not be interfered with.

Having thus fully described my invention, what I claim as new, and desire to secure by Letters-Patent, is:

1. In a locomotive provided with a smoke box, a rotary screen journaled therein, and a rotary cleaner in engagement with the periphery of said screen.

2. In a spark-arrester, a locomotive provided with a smoke box, V-shaped brackets secured therein, a rotary screen journaled in said brackets, a rotary cleaner journaled in two arms of said brackets and provided with means for engaging with the screen and thereby cleansing and rotating the same.

3. In a spark arrester, a locomotive provided with a smoke box, a smoke stack extending down into said box with its lower end extended and scalloped, brackets in the smoke box, a rotary screen journaled in said brackets with its periphery adjacent to said extended and scalloped portion of the smoke stack, and a rotary cleaner journaled in position for engaging with the screen and simultaneously rotating and cleaning the same, said cleaner being provided with projections.

4. In a spark arrester, a locomotive provided with a smoke box, a smoke stack extending down into the same, having its lower end expanded and scalloped, V-

shaped brackets secured to the wall of the smoke box, one of the arms of each of which is perforated near its upper end, a shaft journaled in the lower ends of said brackets, a cylindrical screen on said shaft having its periphery adjacent to the lower end of the smoke stack, a shaft journaled in the perforations of said arms, having a pulley on one end, a cylindrical cleaner mounted on said second-mentioned shaft pro-

vided with projections for engaging with the screen, and means connected with said pulley for rotating said cleaner and screen.

In testimony whereof I have hereunto set my hand in presence of two subscribing witnesses.

JOSEPH H. HINES.
